CLAIM

The ornamental design for a case, as shown and described.

DESCRIPTION

FIG. 1 is an isometric view of a case showing our new design;

FIG. 2 is an isometric view thereof;

FIG. 3 is a front view thereof;

FIG. 4 is a rear view thereof;

FIG. 5 is a top view thereof;

FIG. 6 is a bottom view thereof;

FIG. 7 is a right view thereof; and,

FIG. 8 is a left view thereof.

The broken lines immediately adjacent the claimed surfaces represent boundaries of the claimed design. All other broken lines are directed to environment. The broken lines and unshaded regions bounded by broken lines form no part of the claimed design.
